US00D621207S

(12) **United States Design Patent**
Bodum

(10) **Patent No.:** **US D621,207 S**
(45) **Date of Patent:** **** Aug. 10, 2010**

(54) **TRAVEL MUG CLOSURE**

(75) Inventor: **Jorgen Bodum**, Meggen (CH)

(73) Assignee: **Pi-Design AG**, Triengen (CH)

(**) Term: **14 Years**

(21) Appl. No.: **29/341,558**

(22) Filed: **Aug. 7, 2009**

(30) **Foreign Application Priority Data**

Feb. 9, 2009 (WO) DM/071 370

(51) **LOC (9) Cl.** **07-01**

(52) **U.S. Cl.** **D7/392.1**; D7/396.2; D7/900; D9/443

(58) **Field of Classification Search** D7/532, D7/512, 507, 523, 511, 509, 529, 392.1, 396.2, D7/900, 510; 220/705, 23.83, 710, 709, 220/711, 254.3, 501; D9/716, 719, 439, D9/443, 454; 215/11.6

See application file for complete search history.
